UNITED STATES PATENT OFFICE

2,558,051

LIQUID FUEL VAPORIZER

Sam P. Jones, Dallas, Tex.

Application November 26, 1945, Serial No. 630,786

9 Claims. (Cl. 62—1)

1

The present invention relates to a liquid fuel vaporizer. More particularly, it relates to a liquid fuel vaporizer of the type wherein heat is used as a means for vaporizing the fuel. It incorporates a type of mechanism shown generally in prior Patents Nos. 2,252,261 and 2,255,747 wherein a supply tank of liquid fuel is provided with a standing chamber to receive liquid fuel from the supply tank. The chamber is provided with some heating means to vaporize the liquid within the standpipe. There is a vapor connection between the top of the chamber and the top of the supply tank, together with proper pressure control devices to maintain proper pressure relationship between the two, and to control the flow between the same. The apparatus affords an arrangement in which an excessive pressure in the chamber will force the liquid therein back into the supply tank, and thereby reduce or eliminate the vaporization.

It is an object of the present invention to provide improvements on the foregoing system. More particularly, it is an object of the invention to provide a vaporizer mechanism wherein the parts are so arranged that substantially all of the liquid fuel will be forced back into the tank upon the existence of excessive vaporizer pressures, so that further vaporization is substantially eliminated. A further object of the invention is to provide means to prevent a cycle of vaporization within the chamber itself, caused by thermal-gravity circulation of vapor, and perhaps condensate, within the chamber at times when no vaporization is desired.

Further objects of the invention are to provide a vaporizer of the foregoing kind, with particularly desirable control mechanisms.

A further object is to provide a vaporizer of the foregoing type wherein heating of the liquid in the vaporizing chamber is produced by a burner, and more particularly by a burner that is supplied with fuel generated by the vaporizer itself. Another object is to regulate the operation of the burner as a function of the heat in the vaporizer chamber.

Further objects will appear from the following description and drawings, wherein:

Fig. 1 is a front elevation of the vaporizer mechanism, shown partly in section;

Fig. 2 is a side elevation of the mechanism of Fig. 1, shown partly in section;

Fig. 3 is an enlarged view of the upper part of the mechanism shown in Fig. 2; and

Fig. 4 is an enlarged view of the lower part of the mechanism shown in Fig. 2.

2

Vaporizers of the type herein are those employing liquid fuel of one of the known types, such as a mixture of butane and propane which is in liquid form but which may be readily vaporized for use in gas burning devices, typified by water heaters, stoves, vehicles, power plants, and other domestic or industrial mechanisms.

A supply tank 10 is adapted to contain the liquid fuel. The vaporizer mechanism, generally indicated at 11, is associated with the tank 10. Here, the vaporizer mechanism is included in a suitable casing 12, mounted upon the tank 10 by brackets 13 and 14.

A liquid withdrawal line 15 leads from the bottom of the tank 10 through a manually controlled valve 16. The pipe 15 passes through the housing 12 and is connected into a fitting 17 at the bottom of a standpipe 18, which is supported within the housing 12 by brackets 19 and 20.

The pipe 15 is removably connected into the fitting 17 by a suitable union 22, which provides communication with a passage 23 through the fitting 17 that connects to a central vertical passage 24 in the fitting, which passage 24 opens downwardly and is closed at the top. A vertical tube 25 is threaded at its upper end into the opening 24 and extends downwardly from the fitting 17, terminating in a sloping lower end 26.

A bowl member 29 has a horizontal flange at its upper end, so that it may be secured by bolts 30 to the bottom of the fitting 17. The bowl member provides an inner bowl section 31 that has substantially hemispherical lower walls 32, terminating in a hollow, central, bottom projection 33. This projection 33 has a well or cavity 34 therein to receive the lower sloping end 26 of the tube 25. The sloping end insures flow even if the tube 25 is lowered into contact with the bottom of the cavity 34.

The bowl member 29 has a series of radially extending vertical ribs 36 extending downwardly from the top flange to the bottom of the member. A cover 37 is fitted around the outer ends of these ribs, and secured by means not shown. This cover depends below the bowl member 29 to provide a burner shield.

The fitting 17 receives the lower end of the standpipe 18. Adjacent the bottom of the standpipe 18, there is a strip 40 of some suitable material capable of supporting a gas circulation restricter 41 that may be in the form of a mass of copper mesh (such as copper wool). The member 40 is narrow enough not to block flow from the bowl 29 to the standpipe 18. The restricter 41 is pervious to gas flow, but restricts free flow,

The upper end of the standpipe 18 is connected by a union 42 with a header pipe 43, surmounted by a vent pipe 44. The union 42, as shown in Fig. 3, has a disc 46 medially supported therein, this disc having a port 47 through it. The disc 46 supports a float valve 48, of inverted cup shape, having a synthetic rubber or like diaphragm 49 across its top. This diaphragm is adapted to register with a valve seat member 50 of tubular shape, which member is threaded into a cross pipe 51 that extends through the header pipe 43 on the standpipe 18. The valve seat 50 has a port 52 providing communication from the standpipe and its header to the interior of the pipe 51. It will be observed that the pipe 51 is sealed into the walls of the header 43.

The pipe 51 comprises the outlet pipe of the apparatus. It is connected through suitable elbows and unions to a pressure regulating valve 56, that may be of any conventional type designed to limit the pressure of the ultimately discharged gas to a desirable maximum value.

The pressure regulator 56 discharges into a supply line 57 through a ported union 58. The union 58 receives an end of a burner bypass line 59. A manual valve 60 is included in the main outlet line 57 subsequent to the union 58. A manual valve 61 is shown as controlling the burner line 59.

The bypass line 59 extends into a T 62, and thence to a pilot safety valve 63. This pilot safety valve may be of the thermocouple type, as known in the art, with a heat sensitive element 64 disposed adjacent a pilot flame, as will appear, and controlling the passage of the gas from the pilot line 59.

An outlet pipe 65 leads from the pilot safety valve 63 into a thermostatic valve 66. This valve may be of any of the well known thermostat valve types, having a thermally sensitive element, preferably in the form of a bulb 67 embedded within one of the ribs 36 of the vaporizer bowl 29. The bulb 67 is connected by a suitable capillary 68 to the valve 66, so as to close the valve when a predetermined temperature is reached at the bulb 67. Normally, a snap-action, on-and-off type of control is employed in the valve 66, but it will be understood that the valve may be of the throttling type wherein the burner is modulated as a function of the heat requirement in the bowl.

The valve 66 has an outlet 70 that leads to a main burner 71. The burner 71 has a jet 72 adapted to deliver flame to the bottom of the bowl 32. There is a pilot burner line 73, leading from the T 62, to a pilot burner 74. This pilot burner provides a pilot flame for combustion of fuel at the main burner. The thermocouple element 64 is located to respond to the existence or absence of pilot flame.

The burner structure may be supported on the depending shield 37 by means 75. It will be seen that this shield protects the burners from wind and the like.

Returning to the outlet pipe 51 at the top of the standpipe 18, the opposite end of the pipe 51 leads into a flow control and check valve 76. This check valve has a valve member 77 controlling the flow between the pipe 51 and an opposite pipe 78. The latter is connected through a hand valve 79 to a pipe 80 that opens into the top of the supply tank 10.

The valve 76 is adapted to seat as a check valve when the pressure in the standpipe is higher than the vapor pressure above the liquid in the

tank by a predetermined amount that is a function of the mass of the valve element, and its areas subjected to the two pressures. As will appear, the valve is opened by means responsive to a larger predetermined excess of tank vapor pressure over standpipe pressure.

This latter function is provided by a diaphragm 81 subjected on its upper side to tank pressure, and subjected on its lower side to a spring 82 adjustable by a screw 83. Atmospheric pressure is maintained below the diaphragm by provision of a bleeder port 84. When tank pressure is reduced below a value determined by the spring 82, the diaphragm will move upward, raising a rod 85 and opening the valve 71.

Operation

The operation of the device is as follows:

A supply of liquid fuel is introduced into the tank 10. Normally, this liquid will flow past the valve 16, through the line 15 into the bowl 32 and the riser or standpipe 18 until the levels are equal in the tank and the standpipe. These gases are readily vaporized, and, as a result, there will be a vapor above the liquid in both the tank 10 and the standpipe 18. The pilot burner 74 will be ignited, and the pilot safety valve 63 open.

Assuming a normal operation in which there is a demand for gas into the line 57, there will be a hot condition of the bulb 67 that vaporizes the liquid within the bulb. This vapor will rise through the gas flow arrestor 41 to the space above the liquid within the standpipe 18. Thence it will pass through the opening 47 in the disc 46 and raise the float valve 48 a short distance so as to permit the gas to flow around the lower edge thereof, and thence out through the port 52, through the pressure regulator 56, and into the outlet pipe 51.

Heat may be supplied to the bowl 32 from the burner 72. This burner receives a portion of the gas bypassed through the line 59, through the pilot safety valve 63, the thermostatic valve 66 to the burner. This burner provides enough heat to vaporize adequate vapor for maximum demand. When the bowl member 29 attains sufficient heat to vaporize enough fuel to satisfy the demand, the bulb 67 will close the thermostatic valve 66, shutting off the main burner 72 until the bowl temperature is again lowered. At such time, the thermostatic valve will again open, and fuel will be supplied to the burner 72 and ignited by the pilot flame. As noted, the valve 66 may be of the modulating type, in which it will supply enough fuel to the burner so that the latter may maintain the desired heat delivery for the varying conditions of the vaporizer. Such modulation would preferably employ one of the control valves that modulates between high and minimum flow positions, and cuts off when minimum flow is more than is needed.

It frequently happens that, at the initial demand for gas in the outlet 57, there will be a requirement greater than that available in the standpipe when the system is relatively or wholly inactive, and greater than can be immediately supplied at the start of a burner operation. Such demand is usually in the form of a suction on the line 57. It first withdraws the available gas in the standpipe, lowering the pressure and building up the liquid level therein.

When the demand previously referred to reaches an amount that produces a predetermined pressure excess in the tank top over that in the standpipe, the check valve 76 will unseat, and

vapor present above the liquid in the tank will supply the deficiency in the demand. The particular pressure differential may be chosen to suit the conditions, and is a function of the weight of the valve 11. Typically, when the liquid level in the standpipe rises one or two inches above the level in the tank, the valve 11 will lift, and will remain open until the gas pressure in the standpipe is raised by the heater to reduce the differential below that required to open the valve 11. The reserve of gas thus drawn from the supply tank 10 is usually enough to suffice until the heat can generate a proper supply of gas sufficient to supply the requirement.

If the amount of gas generated from the hot bulb 32 is greater than that required, a vapor pressure will build up in the top of the standpipe 18. This will tend to force the liquid column within the standpipe down, which, of course, drives liquid back into the tank 100. The amount of liquid in contact with the heated lower parts of the standpipe is reduced in this manner, and hence the amount of gas generated is reduced. An equilibrium will be reached wherein the level of the liquid in the standpipe or bowl is just sufficient to supply the demand.

If the generated gas is so far in excess of the requirement, as when the requirement stops altogether, that the liquid in the standpipe 18 is driven completely out of the standpipe, the shape of the bowl 32, with its cavity 34 enclosing the bottom of the tube 25, will cause all of the liquid to be forced back into the tank 10, and there will be substantially no generation of vapor. This is a highly desirable feature of the present arrangement.

When there is little or no gas being drawn off through the line 57, hot gases tend to rise from the bowl 32 into the standpipe 18. As they rise, they become cooled off due to the radiation of heat through the walls of the standpipe, and then, being relatively cool, descend through the rising hot gas. Thus, a thermal circulating system is set up in the standpipe which wastes heat.

The arrestor 41 has been found to prevent this thermal circulation. When little or no gas is being drawn off through the line 57, the circulation of hot gases is confined substantially to the vaporizer bowl 32. The gases that do rise out of the vaporizer into the copper sponge arrestor 41 are cooled off in the sponge and returned back to the vaporizer. Thus, only a very limited thermal circulation is produced, and a greater efficiency of the system results.

The operation of the flow regulation on the valve 16 is similar to that in the earlier patents mentioned. It acts to keep a supply of vapor above the liquid in the tank 10. The liquid in the tank may become excessively cooled, as by lowered atmospheric temperature, to a temperature at which vaporization will stop. The diaphragm 81 is subjected on its upper surface to vapor pressure in the tank, and on its lower surface to force of the spring 82 and atmospheric pressure introduced through the bleeder opening 84. Whenever the vapor pressure in the tank is lowered below a predetermined value, such as 5 p. s. i., the spring pressure will elevate the diaphragm and effect opening of the valve. This will permit vapor from the standpipe to enter the tank 10 above the liquid, which vapor will flow thus until the pressure in the tank reaches the 5 p. s. i. When the vapor pressure in the tank reaches the critical value aforesaid, it will depress the diaphragm 81 and the valve will close of its own weight. An

adequate available supply of such vapor is thereby maintained above the liquid. Also, the temperature of the liquid will be maintained above the critical value below which vaporization cannot occur. As is evident from the description, the critical pressure at which the diaphragm operates can be adjusted by the screw 83.

The float valve 48 will act to prevent drawing liquid from the standpipe. In the event the check valve 16 fails to open, the suction may be great enough to elevate the liquid into the discharge pipe 51. When the liquid reaches the top of the standpipe, it will lift the float valve 48 to seat the diaphragm 49 across the valve seat 50 and prevent flow of liquid into the pipe 51. The suction will add to the seating pressure.

What is claimed is:

1. In a vaporizing system of the kind described, a vaporizing chamber for connection with a supply 20 of vaporizable liquid, said chamber having a bowl member at the bottom thereof, inlet means to introduce liquid from the supply to said bowl member, heating means disposed adjacent said bowl member, thermostatic control means having 25 a heat-responsive element associated with the walls of the bowl to reflect the temperature thereof, and mechanism regulated by the said element to control operation of the heating means.

2. A gas vaporizing apparatus including a liquid 30 chamber, an inlet means for establishing liquid communication between the lower part of said chamber and a supply, an outlet leading from the upper part of said chamber, heating means to introduce heat into the liquid in the chamber and vaporize the same, and valve means to close 35 said outlet, said valve means having operating mechanism responsive to the liquid level in said chamber, and being adapted to close the valve means when the liquid level approaches the outlet, to prevent liquid from passing into the outlet.

3. A liquid vaporizer system, including a vaporizer chamber for connection with a supply of vaporizable liquid, said chamber having a vaporizer bowl at the bottom thereof, an inlet leading 45 into the bowl and connectable with the liquid supply for inflow of liquid into the chamber, an outlet leading from the upper part of the chamber, a connection leading from the upper part of the chamber for connection to the upper part of the supply, valve control means regulating the flow through said connection, a gas bypass connected to the outlet, a main burner adjacent the bowl, a pilot burner, the bypass being connected to the burners, a pilot safety valve and a main burner controlling thermostatic valve in said bypass, and a thermal element for said thermostatic valve disposed to respond to the temperature in the bowl and effect movement of the thermostatic valve toward closed position when the said temperature increases to a predetermined value, and means restricting the heat of the burner to cause the same to be discharged mainly into the bowl.

4. In a vaporizer of the kind described, a vaporizing chamber having a liquid inlet in its lower end for connection with a liquid gas reservoir and a gas outlet at its upper end, the gas outlet having a port for connection with the upper part of the liquid gas reservoir, and having a working port for connection to a work line, heating means to heat the liquid in the chamber and vaporize the same, the pressure of the vapor above the liquid in the chamber determining the liquid level in the chamber, valve means to open said port to the upper part of the reservoir when the gas pressure in the chamber reduces to a pre-

determined value, and valve means responsive to approach of the liquid in the chamber to the gas outlet, to close the outlet and prevent liquid from entering the working port.

5. In a vaporizer of the kind described, a vaporizing chamber having a liquid inlet in its lower end for connection with a liquid gas reservoir and a gas outlet at its upper end, the gas outlet having a port for connection with the upper part of the liquid gas reservoir, and having a working port for connection to a work line, heating means to heat the liquid in the chamber and vaporize the same, the pressure of the vapor above the liquid in the chamber determining the liquid level in the chamber, valve means to open said port to the upper part of the reservoir when the gas pressure in the chamber reduces to a predetermined value, and valve means responsive to approach of the liquid in the chamber to the gas outlet, to close the outlet and prevent liquid from entering the working port, the valve means including a float in the chamber and a valve connected therewith.

6. In a vaporizer of the type wherein vapor generation in the vaporizer greater than withdrawal from the same produces vapor pressures that depress the liquid level and may expel the liquid from the vaporizer; an upright vaporizing chamber to receive liquid to be vaporized having converging bottom walls to produce a narrow bottom portion, a liquid inlet depending into said narrow bottom portion, the inlet being substantially as large as the bottom portion so that when liquid in the chamber is driven down to the liquid inlet there will be only a minimum amount of liquid in the vaporizer; a vapor outlet at the upper end of the chamber for connection to a vapor consuming device; a heating means energizable at most by only a part of the vapor discharged through the outlet to produce heat in amounts distinct from the total amounts of vapor withdrawn from the vaporizing chamber, so that the amount of heat applied may exceed that required for vaporizing the amount of vapor consumed, the heating means being disposed adjacent the vaporizing chamber so as to apply heat at the bottom portion of the chamber adjacent said inlet.

7. The combination of claim 6 wherein the

heating means comprises a vapor burner connected as a branch into the vapor outlet as a branch, to derive vapor from the outlet.

8. In a vaporizer of the kind described; apparatus to reduce the amount of heat required at minimal vaporization conditions; comprising an upright vaporizing chamber, a liquid inlet into the lower part of the chamber, a vapor outlet from the upper end of the chamber for connection to a vapor consuming device; a heating means at the lower end of the chamber to apply heat thereto to vaporize liquid therein; thermostatic means to regulate operation of the heating means in accordance with temperatures at the lower end of the vaporizer; and liquid and vapor permeable circulation restricting means positioned in the chamber above the bottom thereof to provide a limited vaporizing area in the lower end of the chamber below the restricting means, whereby when there is only a small amount of liquid within said limited vaporizing area, its ascent to the upper part of the vaporizer is reduced, and thereby the condensation and subcooling of such vapor in the upper part of the chamber is at least reduced to a great extent.

9. The combination of claim 8, wherein said circulation restricting means comprises mesh type of material having a large surface area.
